UNITED STATES PATENT OFFICE.

CHARLES L. VAN AMBURGH, OF TACOMA, WASHINGTON.

WIRE-WINDING MACHINE.

1,250,705.

Specification of Letters Patent. Patented Dec. 18, 1917.

Application filed March 31, 1916. Serial No. 38,049.

To all whom it may concern:

Be it known that I, CHARLES L. VAN AMBURGH, a citizen of the United States, and a resident of Tacoma, in the county of Pierce and State of Washington, have invented a new and Improved Wire-Winding Machine, of which the following is a full, clear, and exact description.

The object of the invention is to provide a new and improved wire winding machine more especially designed for winding a wire helically around a stave pipe while the latter is being assembled in a ditch or other place, allowing of conveniently placing the machine in position at any point in the length of the pipe, or removing it therefrom whenever it is desired to do so.

In order to accomplish the desired result, use is made of a wire-feeding drum through which extends the stave pipe or other article to be wound with a wire, and means for imparting a helical motion to the said drum around the article.

A practical embodiment of the invention is represented in the accompanying drawings forming a part of this specification, in which similar characters of reference indicate corresponding parts in all the views.

Figure 1 is a reduced side elevation of the wire winding machine as applied to a stave pipe for winding a wire helically around the same;

Fig. 2 is an enlarged side elevation of the wire winding machine as applied;

Fig. 3 is a front end view of the same with the stave pipe shown in cross section;

Fig. 4 is an enlarged sectional side elevation of the same;

Fig. 5 is a face view of the reel for carrying the wire;

Fig. 6 is a similar view of the wire-feeding drum;

Fig. 7 is a similar view of the frame;

Fig. 8 is an enlarged sectional elevation of one of the drum wheels and its mounting;

Fig. 9 is an enlarged transverse section of a portion of the drum and the tension device for the wire;

Fig. 10 is an end elevation of a portion of the driving mechanism for the frame as applied and with a portion of the stave pipe shown in section; and

Fig. 11 is a side elevation of the mechanism for driving the machine by hand.

Heretofore it has been customary, in mak-

ing wooden stave pipes, to manufacture them in a factory in certain lengths and ship them to the point where they are to be laid, providing each length with a suitable collar whereby it may be fastened to the adjacent length. This method has two disadvantages: One is that each joint unless it is perfectly made sets up an appreciable resistance to the flow of the water through the pipe, and the other is that the freight and delivery charges on the finished pipe amount to a considerable sum, especially if the pipe has to be laid in an undeveloped country without roads. To overcome these objections I have devised this machine which will permit the manufacture of the pipe on the ground, it being only necessary to transport the staves, of which the pipe is to be made, the wire and the tar, or other protective covering, these said materials being much easier and cheaper to transport whether in freight cars, ships, or by wagon or pack train, than the completed pipes. Further, the joints of the staves are arranged so that no two adjacent joints come in line and therefore the pipe forms a continuous structure having a much greater strength and less resistance to the flow of water, and therefore greater capacity, than the pipe made up of lengths as in the present practice.

The wire-winding machine in its general construction consists of a wire-feeding drum 20 through which extends centrally a stave pipe 21 or other similar article, and the said drum 20 serves to tightly draw a wire 22 helically around the stave pipe 21 with a view to bind the staves in position and to strongly reinforce the pipe to withstand the pressure of the water or other fluid passing through the pipe. The drum 20 is mounted to rotate and to travel bodily in the direction of the length of the pipe 21, that is, in the direction of the arrow *a* so that for this double movement the wire is helically drawn around the pipe 21. The wire-feeding drum 20 is supported in spaced relation to the pipe 21, and for this purpose the drum 20 is provided with wheels 23 traveling on the peripheral face of the pipe 21. One end of the feeding drum 20 is provided exteriorly with ball bearings 24 on which is mounted a tubular frame 25 through which extends centrally the pipe 21, the said tubular frame 25 having a rearwardly traveling motion 110

in the direction of the arrow *a* whereby the feeding drum 20 is bodily carried along in the same direction.

In order to rotate the wire-feeding drum 20, use is made of a gear wheel 26 secured exteriorly to the drum 20, and the said gear wheel 26 is in mesh with a pinion 27 secured on a shaft 28 extending longitudinally and journaled in a suitable bearing 29 attached to or forming part of the frame 25. The shaft 28 is rotated either by a motor 30 as illustrated in Fig. 1, or by hand power. The motor 30 is preferably an electric motor connected by wires 31 with a suitable source of electrical energy and the motor shaft 32 is provided with a worm 33 in mesh with a worm wheel 34 secured on the shaft 28, thus when the motor 30 is running a rotary motion is given to the shaft 28, and the latter's pinion 27 rotates the gear wheel 26 and consequently the wire-feeding drum 20. In case hand power is used, as shown in Fig. 11, then the shaft 28 is connected by a universal joint 35 with a shaft 36 journaled in a suitable bearing 37 attached to an extension 38 of the bearing 29. The shaft 36 is provided with a suitable hand wheel 39 under the control of an operator for turning the shaft 36 with a view to rotate the shaft 28 and consequently the feeding drum 20, as above mentioned.

The rearward traveling movement given to the frame 25 is actuated from the gear wheel 26 and for this purpose the following arrangement is made: The gear wheel 26 is in mesh with a gear wheel 40 secured on a shaft 41, journaled in a bearing 42 attached to the frame 25. The shaft 41 is connected by a double universal joint 43 with a shaft 44, journaled in bearings 45 mounted in a housing 46 having a bracket 47 attached to the frame 25. The shaft 44 within the housing 46 is provided with a worm 50 in mesh with a worm wheel 51 secured on a transverse shaft 52 journaled in the housing 46. Each outer end of the shaft 52 is connected by a universal joint 53 with a shaft 54 journaled in bearings 55 held on a bracket 56 attached to the frame 25. On this shaft 54 between the bearings 55 is secured a spike wheel 57 having spikes 58 adapted to engage the peripheral face of the pipe 21 so that when the spike wheel 57 is rotated in the direction of the arrow *b* then the frame 25 is moved rearwardly in the direction of the arrow *a*. A number of spike wheels 57 are arranged around the pipe 21 and connected with each other at their shafts by links 60 and a universal joint 61 so that several spike wheels 57 are rotated in unison whenever the shaft 52 is rotated, as previously explained. It is understood that when the machine is running and the gear wheel 26 is rotated then a rotary motion is transmitted by the gear wheel 40 to

the shaft 41 which by the universal joint 43 rotates the shaft 44 and the latter by the worm 50 and worm wheel 51 rotates the shaft 52. By arranging the spike wheels 57 in spaced relation around the pipe 21 it is evident that the frame 25 is moved rearwardly and without danger of the frame turning on its axis. From the foregoing it will be seen that by the arrangement described the wire-feeding drum 20 is rotated on its axis and is moved bodily in a rearward direction by the frame 25 held against rotation. Each of the links 60 is preferably made in sections (see Fig. 10) sliding one on the other to insure proper transmission of the power to the shafts of the spike wheels 57 and without danger of binding.

On the peripheral face of the wire feeding drum 20 is mounted a tension device 70 having a nipple 71 screwed or otherwise fastened to the drum 20 (see Fig. 9). The nipple 71 is provided with a bore 72 for the passage of the wire 22 and this bore registers with a bore 73 formed in the wall of the drum 20 and leading tangentially to the peripheral face of the pipe 21. The outer end of the nipple 71 is provided with a short angular guide pipe 74 for guiding the wire 22 to the tension device. The wire 22 while passing through the bore 72 is pressed on by a rounded off end of a pin 75 mounted to slide in the nipple 71 and provided at its outer end with a crosshead 76 slidingly engaging bolts 77 screwing in the top of the nipple 71. Springs 78 are interposed between the crosshead 76 and the heads of the bolts 77 to force the pin 75 downward in frictional contact with the wire 22 so as to press the same against the bottom of the bore 72 with a view to give the desired tension to the wire prior to its passage onto the pipe 21. By adjusting the bolts 77 more or less tension can be given to the springs 78. It will be noticed that by this tension device the wire 22 is held under tension while being helically wound around the pipe 21 and consequently the wire is drawn tightly around the pipe to securely bind the staves in place and to reinforce the pipe with a view to withstand the pressure of the liquid passing through the pipe.

The wire 22 unwinds from a reel 80 mounted to rotate loosely on the forward end of the wire-feeding drum 20. This reel 80 is constructed as follows: The hub 81 of the reel 80 is provided with an integral forward flange 82 and a removable flange 83 to permit of conveniently placing the coil of wire in position on the hub 81. The flange 82 is provided with a series of studs 84 on which are mounted wheels 85 traveling in an annular groove 86 arranged transversely on the peripheral face of the rear end of the drum 20. Thus by the ar-

arrangement described the reel 80 has a loose, independent rotating movement on the rotating drum 20. The flange 83 is provided at its outer end with spring arms 87 extending onto the peripheral face of the other flange 82 so as to hold the wire from uncoiling in the reel, and to insure proper feeding of the wire to the tension device 80, as will be readily understood by reference to Fig. 2. In practice, the drum 20, the frame 25 and the reel 80 are made in sections separated diametrically and provided with flanges bolted together so as to permit of conveniently placing the several parts on the pipe 21 at any point in the length thereof or for removing the machine from the pipe whenever it is desired to do so. Each of the wheels 23 of the wire-feeding drum 20 is preferably journaled in a bearing 90 held in a plug 91 screwed or otherwise secured to the drum 20 and extending in a radial direction therefrom. The bearing 90 is engaged by a screw 92 screwing in the outer end of the plug 91 to move the bearing 90 inward or outward on the plug 91 with a view to engage the wheel 23 with the peripheral face of the pipe 21. By this arrangement the drum 20 can be readily used on pipes 21 of different diameters. The bearing 90 by being adjustable in the plug 91 permits of setting the wheel 23 at an angle to the axis of the pipe to correspond to the pitch given to the wire 22 wound helically around the pipe 21. Thus the wheels also serve as guide wheels for the feeding drum 20.

The operation is as follows:

When the machine is running and the gear wheel 26 is rotated either from the motor 30 or from the hand wheel 31, as previously explained, then a rotary motion is given to the feeding drum 20 and at the same time a rotary motion is given to the several spike wheels 57 to move the frame 25 rearward in the direction of the arrow *a* thus carrying the feeding drum 20 in the same direction and while the feeding drum is rotating. By this double movement of the feeding drum 20, the wire 22 is drawn firmly around the tube 21 in a helical direction and by varying the tension of the spring 75 of the tension device 70 the wire can be drawn with more or less force around the pipe 21. It is understood that the distance between the convolutions of the helical wire around the pipe 21 depends on the speed with which the frame 25 is moved in the direction of the arrow *a* and by varying the size of the gear wheel 40 and using a corresponding bearing 42 the spike wheels can be rotated at a higher or a lower rate of speed to correspondingly vary the distance between adjacent convolutions of the wire on the pipe 21. In setting up the pipe 21 it is usual to precede the machine with

temporary clamps 100 (see Fig. 1) to hold the staves in place as they are assembled until the machine approaches and winds the wire thereon.

The machine as shown in the drawing fits a pipe of an exterior diameter slightly less than the interior diameter of the drum 20 and in order to permit of using the machine on pipes of smaller diameters the plugs 90 are screwed inward on the drum to engage the wheels 23 with the peripheral face of the smaller pipe, and the spike wheels are changed for larger ones to engage the spikes with the smaller pipe. Thus the same machine can be used on pipes of different diameters. By using different sized driving wheels the longitudinal traveling movement of the frame and drum can be changed without changing the speed of the rotation of the drum, thereby increasing or decreasing the pitch of the spiral wire around the pipe.

Having thus described my invention, I claim as new and desire to secure by Letters Patent:

1. In a wire winding machine, the combination of a wire feeding drum surrounding an article to be wound, means for rotating the drum circumferentially about the article, a frame surrounding the article, to which frame the drum is rotatably connected, and article engaging means mounted on the frame and driven from the drum for moving the frame axially only of the article.

2. In a wire winding machine, the combination of a wire feeding drum surrounding an article to be wound, means for rotating the drum circumferentially of the article, a frame surrounding the article and on which the drum is rotatably mounted, means carried by the frame for engaging the article to move the frame axially of the article, a driven gear on the drum rotatable relatively to the frame, and connecting means between the gear and said frame carried article engaging means for driving the latter.

3. In a machine for winding wire about a pipe or other article, the combination of a wire receiving drum on the article surrounding the same, means for rotating the drum about the article, a tubular frame on which the drum is mounted for rotation, progressing means mounted on the frame for imparting a traveling motion to the frame and drum in the direction of the length of the article, connecting means between the drum and progressing means for driving the latter from the former, a tension device mounted on said drum for directing the wire tangentially onto the peripheral face of the article and drawing it tight thereon, and a wire carrying reel rotatably mounted upon the said drum and movable bodily therewith.

4. A wire winding machine including a drum adapted to surround an article to be wound, means for rotating the drum around

the article, a frame on which the drum is rotatably mounted, means carried by the frame for driving the latter longitudinally of the article, transmission means between the drum and frame carried driving means for actuating the latter from the former, and wire feeding and tensioning devices mounted on the drum.

5. In a wire winding machine, the combination of a drum supported by and surrounding an article to be wound with wire and adapted to have a helical motion around and along the said article, a tension device on said drum whereby resistance to the passage of the wire therethrough is obtained, a frame surrounding said article, means for moving said frame axially along the article and for preventing the rotation of the frame around the article, means for transmitting the motion of the frame to the drum, and means for rotating the drum relatively to the frame whereby a helical motion of the drum relatively to the article is obtained.

6. In a wire winding machine, the combination of a drum surrounding an article to be wound with wire, a series of wheels mounted in the drum and engaging the article whereby the drum is supported by the article and may have a helical motion of any pitch around and along the said article, a tension device on said drum whereby resistance to the passage of the wire therethrough is obtained, a frame axially movable along said article, means mounted on said frame and engaging said drum whereby the drum may be rotated relatively thereto, and means for transmitting the axial motion of the frame to the drum whereby a helical motion of the drum relatively to the article is obtained.

7. In a wire winding machine, the combination of a drum supported by and surrounding an article to be wound with wire and adapted to have a helical motion around and along the said article, a wire holding spool mounted concentric with and supported by said drum and freely rotatable relatively thereto, a tension device on said drum whereby resistance to the passage of the wire therethrough is obtained, a frame axially movable along said article, means mounted on said frame and engaging said drum whereby the drum may be rotated relatively thereto, and means for transmitting the axial motion of the frame to the drum whereby a helical motion of the drum relatively to the article is obtained.

8. In a wire winding machine, the combination of a drum supported by and surrounding an article to be wound with wire and adapted to have a helical motion around and along the said article, a tension device on said drum whereby resistance to the passage of the wire therethrough is obtained, a non-rotatable frame, means mounted on

said frame and engaging said drum whereby the drum may be rotated relatively thereto, means for moving said frame axially along the article, means for connecting the drum rotating means with said frame-moving means whereby the motions take place in fixed relation to each other, and means for transmitting the axial motion of the frame to the drum whereby a helical motion of the drum relatively to the article is obtained.

9. In a wire winding machine, the combination of a drum supported by and surrounding an article to be wound with wire and adapted to have a helical motion around and along said article, a tension device on said drum whereby resistance to the passage of the wire therethrough is obtained, a frame surrounding said article, a series of wheels mounted on said frame and each having spikes extending from their rims adapted to engage the surface of the article whereby when said wheels are rotated said frame will be moved axially along the article, and whereby rotation of the frame around the article is prevented, a gear mounted around the outer surface of the drum adjacent the frame, a second gear with connecting means mounted on the frame and engaging said gear on the drum and rotating said wheels when said drum gear is rotated relatively to the frame, and a driven pinion mounted on said frame and engaging and rotating said drum gear whereby the machine is propelled and operated to wind the wire on the article in a helical path.

10. In a wire winding machine, the combination of a drum supported by and surrounding an article to be wound with wire, and having a helical motion around and along said article, and adapted to wind wire thereon on a helical path, said drum having a groove formed around it near its forward end; of a spool, concentric with said drum and adjacent thereto, and a plurality of wheels engaging in said groove whereby said spool is supported by the drum and is free to rotate relatively thereto.

11. A wire winding machine including a wire receiving drum, means for rotating the drum circumferentially, a frame on which the drum is rotatably mounted, article engaging means carried by the frame whereby the frame may be driven axially, and transmission means between the drum and the said article engaging means.

12. In a machine for winding wire around a pipe or other article, the combination of a tubular frame through which extends the article to be wound with wire, article engaging means carried by the frame for imparting a motion to the frame axially of the article, a wire receiving drum rotatably mounted on the frame, means for rotating the said drum circumferentially, transmis-

sion means between the drum and the article
engaging means for driving the said article
engaging means from the drum, and a ten-
sion device mounted on the drum for direct-
5 ing the wire tangentially onto the peripheral
face of the article and drawing it tight
thereon.

13. A wire winding machine including a
wire receiving drum, means for rotating
10 the same, a frame adapted to surround an
article to be wound, and on which frame
the drum is rotatably mounted, spike wheels

arranged at intervals around the frame and
adapted to engage the article, a flexible
shafting for simultaneously driving the 15
spike wheels, and transmission means be-
tween the drum and said flexible shafting.

In testimony whereof I have signed my
name to this specification in the presence
of two subscribing witnesses.
